UNITED STATES PATENT OFFICE.

MICHAEL FREEMAN, OF RACINE, WISCONSIN.

CONVEYER FOR FEED-CUTTERS.

961,601.

Specification of Letters Patent. Patented June 14, 1910.

Application filed January 13, 1909. Serial No. 472,028.

To all whom it may concern:

Be it known that I, MICHAEL FREEMAN, of Racine, Wisconsin, have invented a Conveyer for Feed-Cutters, of which the following is a specification.

This invention relates to conveyers which are intended especially for carrying ensilage from the feed-cutter to the window or other elevated opening of the silo, although it is also adaptable for use in other relations. Generally heretofore these carriers have consisted of a trough-like casing with one end resting within a stationary boot which is attached to the cutter, and into which it discharges the ensilage which is taken up therefrom more or less imperfectly by the moving conveyer, which consists ordinarily of a pair of endless chains connected at intervals by buckets or cross-sticks. A board or plank is used to support the upper lap of the conveyer, which is the ascending one, and over this board the ensilage is dragged up until it falls off the end thereof in the silo. This common form of carrier is open to several objections. In the first place the ensilage is apt to stick to the flights or cross-sticks as well as the chains, and being carried over with them is dropped from the lower or descending lap of the conveyer upon the ground, where a large amount accumulates in the course of continued operations and has to be collected by hand and re-elevated. Secondly, the ensilage on the ascending plank being open to the atmosphere is largely blown away by the wind. Thirdly, the lower or descending lap of the conveyer requires a special support, to prevent too great tension upon the shafts at its ends and at the same time prevent it from interfering with the opening in the silo. Fourthly, the raising of the ensilage from the boot of the feed-cutter implies necessarily a considerable collection of feed therein, which consequently piles over and clogs the action of the driving-sprocket and conveyer.

The object of my invention is to construct a conveyer which shall avoid these several objections in a simple, cheap and efficient manner.

My conveyer comprises in its construction a plank, forming the mainstay and support for the upper lap of the chain, and a semi-circular gutter or trough attached to the edges thereof on its lower side and forming

the support for the lower lap of the conveyer. At the lower end of the plank is mounted a closed head which substantially replaces the fixed boot ordinarily supplied to receive the ensilage from the feed-cutter, and in this boot is journaled the driving-shaft of the conveyer; and journal-bearings are provided upon said head whereby the latter is adapted to swing vertically upon an axis concentric with the driving-shaft. Means are also provided for propelling the conveyer in a direction such that the lower lap thereof is the rising one, hence the feed instead of being dragged up over the plank is moved upward along the gutter, which being closed no material can escape therefrom.

My invention further consists in the special construction of the conveyer-flights which are made of segmental form, and in the means whereby they are braced against breakage.

My invention further comprises special constructions and combinations which are hereinafter described and particularly pointed out in the claims.

For the better understanding of my invention I have illustrated in the accompanying drawings the most improved form thereof, which is described below in detail.

In these drawings, Figure 1 is a side elevation of a conveyer constructed according to my invention, showing parts of a feed-cutter and silo in connection therewith; Fig. 2 is a longitudinal section on a larger scale of the conveyer separately; Fig. 3 is a plan view thereof; the central portion of the conveyer in this and Fig. 2 being broken out to bring the drawing within limits of the sheet; Fig. 4 is a transverse section on the plane of the line 4, looking in the direction of the arrow; and Figs. 5 and 6 are respectively an end and side view of the hood and delivery-spout on the upper end of the conveyer.

In these drawings every reference letter and numeral refers always to the same part.

In Fig. 1 the conveyer as a whole is designated A, the feed-cutter B and the silo C, in the wall c' of which is the usual opening c² for the insertion of the conveyer. The feed-cutter itself forms no part of the present invention and is merely illustrated in conventional form to illustrate the usual mounting of the conveyer.

110

The details of the conveyer are shown in Figs. 2, 3 and 4. A plank a' sufficiently heavy and strong to form the main support, extends longitudinally of the conveyer and 5 has attached to its edges a semicircular trough a^2 of galvanized iron or the like, reinforced at its upper or delivery end by an angle-iron yoke a^3 or other suitable structure. To the lower end of the plank a' is 10 secured a closed head a^4 , usually made of cast iron, with a hemispherical end a^5 which forms substantially a receiving boot integrally with the conveyer frame, said head being open on its upper side and having up- 15 standing flanges a^6 , a^7 , which form substantially a hopper directly under the delivery nozzle or chute of the feed-cutter to receive the ensilage therefrom. The main or driving-shaft D extends transversely of the head 20 a^4 and it is journaled in bearings a^8 therein and carries in its center a single sprocket-wheel d' , and at one end outside the head a^4 a driving pulley d^2 or other means for rotating the shaft. It will be seen from the 25 drawing that the bearing-lugs a^8 formed on the head a^4 are themselves turned exteriorly to form journals a^9 , which are received in bearing-members E secured by bolts e' or other means to the legs b' of the feed-cutter. 30 On the opposite end of the plank a' are secured a pair of parallel bars a^{10} which extend beyond the ends of the plank and carry a stationary shaft F , on the center of which turns a sprocket-wheel f' provided with an 35 oil-chamber f^2 for lubricating it. The ends of the shaft F are secured in holding-blocks f^3 which have longitudinal extensions f^4 lying against the sides of the bars a^{10} and sliding thereon, being connected thereto by 40 bolts f^5 which are each movable in a slot f^6 in one of the two members. Adjusting-screws f^7 connecting the blocks f^3 with the outturned ends a^{11} of the bars a^{10} are utilized 45 for moving the shaft F longitudinally and thus drawing the conveyer-chain to proper tension.

The conveyer-chain G passes over the two sprocket-wheels d' and f' and as shown lies centrally of the conveyer, carrying at intervals 50 a series of transverse flights g' . These flights, as shown at the right of Fig. 3 and in Fig. 4, are each made up of a segment-shaped board or plank secured to the sides of the conveyer-links by socket-pieces g^2 , g^3 , 55 one of which is longer than the other so that the rivets g^4 passing through the board at their ends do not traverse the same fibers of the wood and thereby avoid a tendency to split. The splitting or breaking off of the 60 edges of the flight is still further avoided by a pair of longitudinal pins g^6 passing transversely of the grain to the sides of the flight and through holes in the socket-pieces g^2 , g^3 riveted at their outer ends in the edges of 65 the flight. This construction is strong, light

and simple and prevents breakage of the flights even if there should be a weakness or actual fracture parallel to the grain of the wood, because the rivet-pins g^6 continue to hold the material in place.

It will be observed that the shape of the flights g' is such as to conform to the bottom of the trough a^2 and thus positively move the ensilage along said trough, the shape thereof preventing the ensilage from passing around the ends or over the tops of the flights as where ordinary sticks are used upon a flat board. The pulley d^2 is turned in a counterclockwise direction as seen in Fig. 2 so that the lower lap of the chain ascends, moving with it the ensilage which drops upon the bottom of the head a^4 , and falls out at the upper end of the trough a^2 , thus being at all times free from the chain G and ensilage which might stick thereto on passing out of the silo is conveyed over the board a' and down into the head a^4 again, so that it is impossible for it to fall upon the ground. A pair of guide-plates a^{13} are secured to the upper edge of the plank a' , the free ends of which are curved downwardly to guide the edges of the flights and prevent them from becoming caught or engaged with the edge of the plank. The head a^4 as shown and as preferably made consists of two parts divided along the center-line of the shaft D and united together by connecting-strips a^{12} .

In Figs. 5 and 6 is shown means whereby I enable the ensilage to be deposited at any point in the silo without moving the conveyer. To the side-bars a^{10} or other convenient part of the conveyer at the upper end is attached a hopper or funnel H in position to receive the ensilage as it falls from the trough a^2 , and over the outer end thereof is placed a hood h' to prevent ensilage from falling over the end of the hopper or being carried thereover by the flights as they turn around the sprocket-wheel f' . The lower end of the hopper H is provided with a flange h^2 on which is rotatably mounted a chute h^3 by means of a groove-ring h^4 secured to its upper end and engaging with the flange h^2 , as shown in Fig. 6. On the lower end of the chute h^3 is mounted a hinged spout I upon a hinge-pin i' and which has a rock-arm i^2 secured thereto, to the end of which is attached a cord i^3 passing over a pulley i^4 on the side of the chute h^3 , so that by adjusting the cord i^3 , which can be done from the silo below, the chute I can be raised or lowered and thus the ensilage falling therethrough directed to a point more or less to one side of the hopper as desired. A second cord h^5 passes around the groove in the ring h^4 and may be attached to one point thereof, the two ends of said cord passing over pulleys h^6 on the sides of the carrier as shown in Fig. 6 or of the silo as shown in Fig. 1, thence down to a convenient point 130

within the silo, so that by pulling on either cord and releasing the other the chute and spout may be rotated about the vertical axis in a swiveling manner and thus the 5 current of ensilage directed in any desired angular direction.

While I have hereinabove shown the most improved form of my invention, I wish it understood that not all of the features are 10 essential thereto or necessarily made in the exact form shown, but various changes and modifications in the constructions as herein shown may be made without departing from the spirit of my invention, and I wish it 15 understood therefore that the latter is not otherwise limited than by the reasonable scope of my claims.

Having thus described my invention, what I claim as new and desire to secure by Letters Patent is:

1. In a conveyer, a longitudinal plank, a semi-circular trough attached to its edges, a reinforcing yoke at the delivery end thereof, a closed head secured to the lower end of 25 said plank with a hemi-spherical end forming a receiving boot, said head being open on its upper side and having upstanding flanges to form a hopper, a driving shaft extending transversely of said head and 30 journaled in bearings therein, said bearings being turned exteriorly to form journals.

2. In a conveyer, a longitudinal plank, a semi-circular trough attached to its edges, a reinforcing yoke at the delivery end thereof, 35 a closed head secured to the lower end of said plank with a hemi-spherical end forming a receiving boot, said head being open on its upper side and having upstanding flanges to form a hopper, a driving shaft 40 extending transversely of said head and journaled in bearings therein, said bearings being turned exteriorly to form journals, parallel bars secured to the upper end of said plank and extended beyond the end of the

latter and provided with bearings for a stationary shaft. 45

3. In a conveyer, means for nonsplittably mounting a bucket or flight comprising, in combination, a plate of splittable material, a pair of sockets on opposite sides of the center each having a pair of legs flanking opposite sides of the plate, a rivet for each socket at its ends passing through said plate and connecting the two legs thereof, the legs of one socket being longer than those of the other, the rivets passing through the extreme ends of the socket, and a pair of pins passing edgewise through the material of the board transversely of the grain thereof and having one end headed over the base of 60 one of the sockets and the other end headed over the edge of the plate.

4. In a conveyer, a longitudinal plank, a semi-circular trough attached to its edges, a reinforcing yoke at the delivery end thereof, 65 a closed head secured to the lower end of said plank with a hemi-spherical end forming a receiving boot, said head being open on its upper side and having upstanding flanges to form a hopper, a driving shaft 70 extending transversely of said head and journaled in bearings therein, said bearings being turned exteriorly to form journals, parallel bars secured to the upper end of said plank and extended beyond the end of 75 the latter and provided with bearings for a stationary shaft, holding blocks having longitudinal extensions lying against the sides of said bars and sliding thereon, said blocks supporting the ends of said stationary shaft, 80 and means for adjusting said blocks.

In witness whereof, I have hereunto set my hand this 11th day of December, 1908.

MICHAEL FREEMAN.
